**METHOD OF MOORING A SHIP TO A
MOORING DEVICE**

Arne Sekkelsten, Arendal, Norway

Continuation of application Ser. No. 466,279, June 23, 1965. This application Mar. 1, 1967, Ser. No. 619,644
1 Claim. (Cl. 114—230)**ABSTRACT OF THE DISCLOSURE**

A method for mooring a ship to a dock or buoy in which there is a drum having a fixed flange separating the drum into two portions, there being a slot in this flange through which a rope can pass. The portion of the drum on one side of the flange serves as a storage drum portion, on which the full length of rope is stored when the winch is not in use, and from which the rope is payed out to moor the ship, the portion of the drum on the other side of the flange being a tension drum portion, on which a small length of rope is wound in one layer only by back-spooling after the free end of the rope has been secured to a mooring post or buoy.

This invention relates to improvements in mooring winch drums and is a continuation of my copending application, Ser. No. 466,279 filed June 23, 1965 and now abandoned.

It is usual on board ships to use winches for mooring to a dock, buoy or the like. In recent years it has become usual to employ automatic mooring winches i.e. winches that can keep the mooring rope suitably tight even if the rope length changes because of tide and variation in draft during loading and unloading. The mooring rope is usually brought to the winch drum, and the demand for storage capacity usually is so large that the rope must be spooled in several layers on the drum, unless the drum is made impractically long. Having several layers of the rope on the drum presents two great disadvantages. In the first place the pull of the winch decreases with increase in diameter, as the applied torque is constant. Secondly the rope easily penetrates into the underlying layers and is damaged when there is a large tension in the rope and several layers of rope. This all too readily happens when the underlying layers are loosely spooled, and loose spooling usually occurs during mooring operations, as the rope is payed out slackly before it is heaved in with a large pull of the winch.

In order to eliminate these disadvantages, the present invention provides a drum for a mooring winch in which the drum has a fixed separating flange which divides the drum into two compartmented units or portions namely a rope storage portion and a portion for rope under tension (tension portion hereafter), and the said flange has a slot in which the rope is laid across from the storage portion to the tension portion when the rope has been payed out from the storage portion and has been secured to the mooring posts or buoys. In automatic ship mooring gear according to the present invention, a long length of the rope can thus be stored in the storage portion of the drum without the pull of the winch upon the rope being reduced as the diameter due to the plurality of layers increases, and without the loaded rope penetrating into underlying layers and damaging the rope. At the same time, the rope, which normally lies in just one layer in the tension portion of the drum can be loaded into this portion after a few security turns, with the maximum pull of the winch. Stated in another way and as shown clearly in FIGS. 1 and 3 of the drawings of the parent application Ser. No. 466,279, the whole length of rope present on the power drum portion is payed out and then

2

spooled-back after the rope has been disengaged from the mooring as the ship is ready to leave on to the storage drum portion, while the rope extends through the slot and lies unloaded in the storage portion.

Mechanism has previously been proposed in which two drum parts are bolted together and the partition between the two drum parts on one side has a radial slot through which rope can be laid. This prior mechanism merely adjusted the working length of the rope in actual use on the working part of the drum in accordance with the depth of the well or bore hole. The working length being defined as the length of rope payed out and heaved in during each cycle of operations.

According to the invention, however, the rope length on the tension part of the drum is only a few turns, sufficient to give the rope friction contact with the drum, so that it passes unstressed through the slot to the storage part. The major portion of the rope which takes part in the actual mooring of the ship extends from the dock to the winch. This portion is not wound up on the tension part of the drum. The rope length on the tension part of the drum thus is independent of the length of rope from the dock to the ship.

The present invention is further described below with reference to the embodiment shown, by way of example in the accompanying drawing, wherein:

FIG. 1 schematically shows an axial section through a winch drum according to the invention, and

FIG. 2 is a cross-section through the drum in FIG. 1 on the line A—A of FIG. 1.

FIG. 3 shows the embodiment of the invention seen in perspective view.

FIG. 4 is a view in elevation of a ship moored to a dock in accordance with the present invention.

In the drawing a drum 1 is shown with an axially fixed separating flange 2, one portion of the drum, namely a storage portion 3, serving to store rope 4. The other portion, namely a tension portion 5, is used for the surplus length 6 of the rope with which the winch works during a mooring operation (in addition to the necessary security turns, which usually number from three to five). Between the storage portion and the tension portion the rope extends through a slot 7 in the separating flange 2. 9 represents an automatic mooring actuating means of known kind, e.g. such as described and illustrated in Bulletin of the Society of Naval Architects and Marine Engineers, November 1956, pages 9-12.

When the winch is in use, as much rope is payed out from the storage portion 3 as is necessary to reach the mooring bit on the dock plus a sufficient surplus length to allow for variations in the length of rope due to tensioning on heave-in and to movement of the ship relative to the dock, e.g. caused by tide and by loading or unloading the ship and also the necessary security turns. The rope is laid in the slot 7 and the security turns and the surplus length are laid on the tension portion 5 by back-spooling.

When the ship is to cast off, the whole length of rope present on the tension drum portion is payed out to slacken the rope. Thereafter the full length of free rope is spooled back on the storage drum portion so as to be ready for pay-out from that drum portion the next time the ship is to be moored.

What is claimed is:

1. A method of mooring a ship comprising the following steps:

upon arrival of the ship in correct position for mooring paying out rope from a storage drum portion, securing the free end of said payed-out rope to a mooring device,

shifting the run-off portion of the rope from the storage drum portion to a tension drum portion rotatable in unison therewith,
 rotating said drum portions in the reverse direction to spool-back rope on said tension drum portion until 5
 the rope has acquired a predetermined tension,
 during the stay of the ship turning said two drum portions slightly back and forth to substantially maintain said predetermined tension,
 preparatory to departure of the ship from the mooring 10 device, paying out the whole length of rope present on the tension drum portion,
 shifting the run-off portion of the rope from said tension drum portion to said storage drum portion, and spooling-back the full length of free rope on said storage drum portion.

shifting the run-off portion of the rope from said tension drum portion to said storage drum portion, and spooling-back the full length of free rope on said storage drum portion.
